HANGER FOR DISPLAYING SOCKS

Bernard B. Levine, 530 E. 90th St., and Otto L. Becker,
336 College Road, both of New York, N.Y.

Filed Aug. 1, 1960, Ser. No. 61,580

Term of patent 14 years

(Cl. D80—8)

FIG.1

Fig. 1 is a front elevational view of a hanger for displaying socks showing our new design;

Fig. 2 is a top view thereof; and

Fig. 3 is a front edge view thereof.

The rear of the hanger for displaying socks is substantially like the front shown in the drawing.

We claim:

The ornamental design for a hanger for displaying socks, substantially as shown and described.
